UNITED STATES PATENT OFFICE.

JOHN S. STEVENSON, OF CRISFIELD, MARYLAND.

WHIP-SOCKET.

970,658.

Specification of Letters Patent. Patented Sept. 20, 1910.

Application filed June 21, 1909. Serial No. 503,289.

To all whom it may concern:

Be it known that I, JOHN S. STEVENSON, a citizen of the United States, residing at Crisfield, county of Somerset, State of Maryland, have invented a new and useful Improvement in Whip-Sockets, of which the accompanying drawings and description are a specification.

The object of my invention is to provide a whip socket having a lock mechanism;—first, to secure a whip in the socket, and second, to secure the socket to the dash-board of a carriage or wagon:—the mechanism so arranged that before the socket can be unlocked to allow removal from the dash-board, it will be necessary first to unlock the whip. And by a novel construction of the lock, one key will operate the two sides of the lock, for the purpose above stated.

By referring to the drawings, Figure 1, is a side elevation illustrating the whip socket attached to a dash-board: Fig. 2, a vertical elevation with the cover of the lock removed and showing the lock mechanism closed:—Fig. 3, a vertical elevation with the cover of the lock removed and showing the lock mechanism open:—Fig. 4, a perspective of the cover of the lock showing the straps for attaching the socket to a dash-board, and method of attaching the straps to the cover of the lock, and the lugs for engaging the mechanism for holding the cover to the case of the lock:—Fig. 5, a vertical cross section of the socket and locking jaws therein for holding a whip, with the mechanism of the lock in side elevation:—Fig. 6, a vertical cross section taken on line X X of Fig. 2:—Fig. 7, a vertical cross section taken on line X X of Fig. 3:—Fig. 8, a top plan view of the socket with the whip in cross section, and top of the case inclosing the lock removed:—Fig. 9, a plan of the key.

In all the views of the drawings like numbers denote like parts.

The invention consists of a tubular body 1 and hollow offset 2:—preferably one casting. The inner diameter of 1 is decreased to effect two inclined surfaces 3 and 3^a, and immediately thereunder are two jaws 4 and 4^a, fulcrumed and pivoted at 5 and 5^a to a plate 6, which also serves as a seat for the whip. The lower ends of the jaws are engaged by a contracting spring 7, and one jaw, 4^a, has a flared recess 8, as in Figs. 5, 6, and 7, and which is engaged by a pin 9, passing through

slot 10, and integral with sleeve 11, slidably mounted upon a movable bar 12. This bar 12 rides in a shouldered aperture 13 in the bottom of the offset 2 and in a pedestal 14, 60 and fixed upon the bar 12 is a perch 15, which serves as a seat for a spiral spring 16, upon which rests the sleeve 11, as shown in Figs. 2, 3, 5, 6 and 7.

Lugs 17 and 17 integral with the wall of 65 the offset 2, guide a bar 18, which rests between two spiral springs 19 and 19^a:—the former being the heavier for a purpose hereinafter set forth. This bar, 18, is rectangular at two points, 20 and 20, the purpose 70 therefor to be hereinafter stated. The upper end of the bar 18 has attached thereto, by means of a screw, 21, a pawl 22, the upper lip of which, 22^a, is longer than the lower lip 22^b, as in Figs. 2 and 3. 75

A lever 23 engaged by a spring 24 is mounted by a screw 25 to the bed of the offset 2, and the upper part of lever 23 has a tongue 23^a entering the recess between 22^a and 22^b of the pawl 22, and the lower part 80 of lever forms a shoulder 23^b for seating the perch 15, when the mechanism is closed as shown in Figs. 2, 5 and 6.

The cover for the lock is a plate 26 and auxiliary plate 26^a as in Fig. 4. Integral 85 with the plate 26 are two lugs 27 and 27 having vertical cylindrical openings 27^a and 27^b corresponding to the round portion of bar 18, and entering the openings 27^a and 27^b are channels 27^b and 27^a corresponding in 90 width to the width of the rectangular section, 20 and 20, of the bar 18. The object of wing 28 integral with plate 26 will be hereinafter stated.

Two straps 29 and 29, as in Figs. 4, 5, 6, 95 7 and 8, are U shaped and near the ends thereof have annular grooves 29^a and 29^a as in Fig. 8. The ends of the straps pass through apertures in the plate 26 and through apertures 30, 30 etc. in the auxiliary plate 26^a, as in Fig. 4. The apertures 30, 30 etc. are extended as parallel openings 30^a, 30^a etc. Fig. 4, of a width to enter the annular grooves 29^a and 29^a, Fig. 8, so that when the ends of the straps are 100 passed through the apertures when they are coincident, a downward movement of auxiliary plate 26^a, will cause the parallel openings to engage the annular grooves and hold the straps, as in Fig. 4. 105

The straps 29 and 29 encircle the iron frame of the dash-board as shown in side 110

elevation in Fig. 1. The straps are secured as described and shown in Fig. 4. Then one side of the plate, 26, is entered under the lip or inward extension 31 of the offset 5 2 as in Fig. 8, and the key upon forcing the bar 18 upward until the rectangular sections 20 and 20 are opposite the channels 27^b and 27^b of the lugs 27 and 27, allows the plate 26 to fall in place and rest upon the face 10 of the offset 2, thereby covering the lock mechanism as shown in Figs. 1, 5, 6, 7 and 8. The cover is then locked to the offset 2 upon withdrawing the key and allowing spring 19 to force down bar 18 until the round part 15 thereof enters and engages the vertical cylindrical openings 27^a and 27^a, as in Fig. 5.

Therefore, with the construction and arrangement of the parts described, we will proceed with the operation of the invention, 20 which is as follows:—Assuming a whip to be securely locked in the socket, as in Figs. 2, 5 and 6, it is released for removal by the following operation, when the mechanism is in position as shown in Fig. 2:—The key 25 is inserted in the horizontal key-hole, Fig. 1, which corresponds to the line marked “Whip” in Fig. 2, and is seated in a recess 32^a in the offset 32, Fig. 5, and as the wing 28 integral with plate 26 prevents the key 30 from being turned upward, it follows that a clock-wise movement of the key will bring it in contact with the blade 18^a integral with the bar 18, Fig. 5, and forcing down bar 18 will cause pawl 22 through lip 22^a to engage 35 tongue 23^a of the lever 23, and moving lever 23 aside until the shoulder 23^b releases the perch 15, as in Figs. 3 and 7. As the spring 16 between sleeve 11 and perch 15 is under compression when the mechanism is closed, 40 as in Figs. 2 and 6, the reaction of the spring when perch 15 is released from shoulder 23^b, will force down bar 12, as in Figs. 3 and 7, and the weight of the whip resting on plate 6 will cause the jaws 4 and 4^a to 45 drop, with consequent movement of pin 9 and sleeve 11, until the jaws are free of impingement with the inclined surface 3^a, and will then be opened by the contracting spring 7, as in Fig. 7, thereby freeing the 50 whip of the locking mechanism and allow its removal.

To remove the socket from the dash-board, the operation is as follows:—First, the whip 55 must be unlocked and the mechanism in the position shown in Figs. 3 and 7, inasmuch as with tongue 23^a of the lever 23 free of the recess between lips 22^a and 22^b of the pawl 22, as in Fig. 3, and when the bar 18 is moved upward, lip 22^b will pass the end of tongue 23^a, and as the lower end of the lever 23 is resting against perch 15, the spring 24 can not move lever 23 and cause 23^a to interfere with 22^b when bar 18 is moved upward. Therefore, the key is inserted in the 60 vertical key-hole shown in Figs. 5, 6 and 7,

which corresponds to the line marked “Socket” in Fig. 3, and finds a seat in offset 33, Fig. 3. The key when turned clockwise, considered from the operating side, carries bar 18 upward by engaging indention 18^b, Fig. 5, until the rectangular sections 20 and 20 are opposite channels 27^b, 27^b in the lugs 27, 27, Figs. 4 and 5, at which point the socket with integral rectangular offset, containing the lock mechanism, may 70 be removed from plate 26. The auxiliary plate 26^a, when moved upward, releases straps 29, 29, and disengages them from the frame of the dashboard. Upon withdrawing the key, spring 19 returns bar 18 to its normal position against spring 19^a, with the lip 22^a resting on tongue 23^a, as in Fig. 3.

To lock a whip in the socket, and assuming the socket attached to a dash-board, the mechanism may be either open or closed as 85 in Figs. 2, 3, 5, 6 and 7. For the first description we will consider the mechanism open as in Figs. 3 and 7. Therefore, the whip dropped in the socket is guided by the inclined surface 3 clear of the ends of the 90 jaws 4 and 4^a to rest upon the plate 6, and then by pushing upward bar 12, the movement is imparted through spring 16, sleeve 11 and pin 9 through slot 10 and flared recess 8 to the jaws 4^a and 4, until the jaws 95 coming in contact with the inclined surface 3^a, are converged and grip and hold the whip. Should the handle of the whip be unusually large, hence allowing only a slight 100 upward movement of the jaws on the inclined surface, the bar 12 will be free to continue the upward movement, by reason of the compressible spring 16, between perch 15 and sleeve 11, until the perch 15 is opposite shoulder 23^b at which time the spring 24 105 will cause lever 23 to close and seat the perch on the shoulder, as in Figs. 2, 5 and 6, after which the whip can not be removed without first operating the lock mechanism with the key. An attempt to remove the whip by 110 first pressing down, followed by a quick upward movement, will be frustrated, inasmuch as, the downward movement compresses spring 16, hence the reaction of the spring 115 instantly causes the jaws to coincidentally follow the upward movement of the whip, and by reason of the inclined surfaces, close the jaws to grip and hold the whip.

To insert and lock a whip in the socket when the mechanism is closed as in Figs. 120 2, 5 and 6, we must first assume the socket empty and the jaws so far up that the upper ends thereof are in contact, by reason of the influence of the inclined surface 3^a. Hence, the whip is inserted and meeting the 125 contracted jaws, continued pressure forces the jaws down to beyond the inclined surface and to open by reason of the spring 7, and also compressing spring 16, until the opening of the jaws allows the whip to pass and 130

the butt to rest upon plate 6, and by releasing the whip, the compressed spring 16 will return the jaws until converged by 3^a against the whip, as in Figs. 5 and 6.

5 The reason the socket can not be unlocked and removed from the dash-board until after the whip is unlocked, will be more clearly understood by referring to Figs. 2 and 3. For it will be noticed that lip 22^b shown in 10 dotted line in Fig. 2, rests immediately under tongue 23^a, hence the key inserted in the vertical key-hole designated by the line marked "Socket" in Fig. 2, can not move the bar 18 and pawl 22 upward. Therefore, 15 the whip must first be unlocked to throw lever 23 aside in order to clear tongue 23^a of lip 22^b, as in Fig. 3.

The perch 15 slightly over-laps and bears 20 against lever 23 as in Figs. 2 and 3, and in conjunction with contact upon the bed of the offset 2, prevents bar 12 from turning on its axis.

The bottom is riveted to the socket after 25 the jaws are in place, and a small orifice 34, Figs. 5, 6 and 7 provides for the egress of rain or dust.

The indentures in the key are made to clear the bar 12 and offset 32 when used 30 from the side having the vertical key-hole. And various indentures may be made and other barriers provided, in order to effect 35 slight differences in the unlocking of the mechanism.

Various modifications may be made in the 35 design and mechanism without departing from the spirit of the invention, and I therefore do not wish to be limited to the exact construction shown.

Having fully described my invention, what 40 I claim as new and desire to secure by Letters Patent, is,

1. In a whip socket, a tubular member and a hollow rectangular member integral therewith, inclined surfaces in the tubular member, pivoted jaws below said surfaces, a bar in the rectangular member carrying a seat, spring, sleeve and pin for operating said jaws, in combination with a bar and pawl operated by a key for moving a lever to release 45 the seat, spring, sleeve and pin in order to effect the opening of said jaws, substantially as and for the purpose set forth.

2. In a whip socket, a tubular member and a hollow rectangular member united, inclined surfaces in said tubular member and pivoted jaws below the inclined surfaces, in 50 combination with a bar and pawl integral

therewith and operated by a key for moving a lever to release a bar carrying a seat, spring, sleeve and pin analogous to the jaws, 60 in order to allow said jaws to drop and be opened by a spring below their fulcrums, substantially as and for the purpose set forth.

3. In a whip socket, a tubular member and a hollow rectangular member, pivoted jaws below the inclined surfaces in the tubular member, a bar in the rectangular member carrying a pin, sleeve, spring and seat for moving said jaws, in combination with a 70 lever supporting said seat and actuated by a pawl integral with a bar moved by a key, for releasing the bar carrying the spring, sleeve and pin in order to allow the jaws to drop below the inclined surfaces and be 75 opened by a spring under their fulcrums, substantially as and for the purpose set forth.

4. In a whip socket, a tubular member and a rectangular member:—the tubular member 80 having inclined surfaces for converging jaws to encircle a whip:—and a pin, sleeve, spring and seat upon a bar to impress the jaws upon the inclined surfaces in the tubular member, in combination with a spring actuated lever 85 to enter under said seat of the bar with the spring, sleeve and pin when the bar is moved upward, to hold the jaws against the inclined surfaces, substantially as and for the purpose set forth.

5. In a whip socket, a rectangular member having a bar with a pawl for engaging a lever:—to lock or release a bar carrying a seat, spring, sleeve and pin adjacent to pivoted jaws in the tubular member:—the said 95 pawl non-operative after the seat, spring, sleeve and pin have been released, in combination with a plate to engage one side of the rectangular member and having lugs for engaging the bar with the pawl, the lugs disengaging from the bar, when the bar is operated in a direction opposite to its movement to release the whip, said plate provided with an auxiliary plate having means for securing two metal straps, substantially as and 100 for the purpose set forth.

In testimony whereof I have signed my name to this specification in the presence of two subscribing witnesses.

JOHN S. STEVENSON.
